OPERATIVE MECHANISM FOR LOCOMOTIVE CYLINDER COCKS

Ralph A. Light, Cynwyd, and Joseph W. Price, Jr., Philadelphia, Pa., assignors to The United States Metallic Packing Company, Philadelphia, Pa., a corporation of Pennsylvania

Application November 3, 1934, Serial No. 751,272

2 Claims. (Cl. 121—134)

Our invention relates to locomotives provided with cylinder cocks of the type in which an exhaust or outlet valve is opened and closed by the movement of a piston working in a cylinder, an open end of which extends into the chamber of the cylinder cock and the other end of which is connected with a conduit for pressure fluid connected with a source of pressure fluid and opened and closed by a valve actuated from the cab of the locomotive, the pressure fluid acting on the piston to move it in a direction to close the outlet valve and means being provided, as a spring, tending to move the piston in a direction to open the outlet valve. A typical cylinder cock of the kind in question is described and shown in the patent to McLain, 1,958,091, of May 8, 1934. As heretofore operated, the outlet valve in such cylinder cocks will remain closed as long as the cab valve controlling the conduit leading from the source of fluid pressure remains open except at such times as the pressure in the chamber of the cylinder cock may exert sufficient pressure on the piston to move it in a direction to open the valve. It is desirable, however, that whenever the steam is cut off from the driving cylinders of the locomotive, as by the actuation of the throttle valve, that the outlet valves of the cylinder cocks should be open and it is also important that whenever the throttle valve is opened and steam delivered to the driving cylinders that the outlet valves of the cylinder cock should be promptly closed and the object of our invention is to provide in the conduit by which pressure fluid is led to the cylinder cocks a second valve located between the valve controlled from the cab and the cylinder cocks and a means for actuating it by which the valve is closed whenever the throttle valve of the locomotive is closed and opened whenever the throttle valve is opened to admit the flow of steam from the boiler to the driving cylinders so that while the connection from the source of fluid pressure to the throttle valve is still controllable by the engineer from the cab, the connection between the source of fluid pressure and the cylinder cocks will be automatically cut off when the throttle valve is closed and automatically opened when the throttle valve is opened, provided the cut off valve controlled by the engineer is also at the time open.

The nature of our invention will be better understood as described in connection with the drawing which illustrates apparatus well adapted for its practical use and employment and in which

Figure 1 is a diagrammatic side elevation of a locomotive provided with our improvement.

Figure 2 is a front end elevation of the locomotive.

Figure 3 is a sectional elevation of the second valve controlling the pressure fluid connection with the cylinder cocks, together with its actuating mechanism.

Figure 4 is a cross-section on the line 4—4 of Fig. 3, and

Figure 5 is a sectional elevation of a cylinder cock.

A indicates the steam dome of the locomotive boiler. B indicates the cab of the locomotive. C, C, the driving cylinders, C¹, C¹, the cylinder valve chambers. D indicates the steam pipe for supplying steam to the locomotive cylinders, D¹, D¹, the branches of the steam pipe leading to the cylinders on opposite sides of the locomotive. E indicates the throttle valve controlled by the 20 throttle lever in the cab, indicated at E¹. F, F, etc., indicate the cylinder cocks, one being connected with each end of the driving cylinders, as shown. These cylinder cocks are constructed as described and shown in the McLain Patent 25 No. 1,958,091, the cock having a chamber F¹ connected to the end of the driving cylinder and having an outlet port at its bottom as indicated at F². This port is opened and closed by a slide valve indicated at F³ and the slide valve is actuated by a rod F⁴ forming an extension of a piston F⁵ working in a cylinder F⁶, one end of which opens into the chamber F¹ and the other or outer end of which is connected to a conduit for fluid under pressure, indicated at G². A 35 spring F⁷ exerts resilient pressure on the rod F⁴ in a direction to move the rod and piston in a direction which will open the valve F³.

G is a conduit for fluid under pressure connected to a source of pressure fluid, as shown, with the steam dome of the locomotive although it should be understood that a reservoir of compressed air may serve as the source of the pressure fluid. Located in the pipe or conduit G is a valve in the cab of the locomotive and diagrammatically indicated at H, by means of which the supply of pressure fluid can be cut off at will and exhausted from the delivery side of the valve. As shown, this valve is of the ordinary plug type but it will be understood that any valve functioning to close the conduit and vent the portion on the delivery side may be used. G¹ is a continuation of the pipe or conduit G connected by branches, as indicated at G², with the individual cylinder cocks.

Located between the conduit G and its continuation G¹ is a valve casing J having an inlet port J¹ connected with the pipe G and an outlet port J² connected with the pipe G¹. The inlet port J¹ connects with the valve chamber J³ from which a port J⁴ connects with the outlet port J² and is opened and closed by a poppet valve J⁵, a spring J⁶ being located in the valve chamber so as to act with resilient pressure to move the poppet valve to seated position. The lower end of the valve chamber J³ is closed by a cap J⁷ in which is formed a vent port or passage indicated at J⁸ which is opened and closed by a valve indicated at J⁹. A spring J¹⁰ acts on this valve in a direction which will tend to move it away from its seat and open the port. Connected with the top of the valve casing J is a cylinder J¹¹, the connection being formed, as shown, by a neck J¹², through which is formed a cylindrical passage J¹³, opening at its lower end into a chamber J⁴ forming a part of the passage between the port J⁴ and the outlet port J². The upper end of the cylinder J¹¹ is connected by a pipe K with the steam pipe, as shown with one of the branches D¹ and the connection should be made, as shown, at a point in the steam pipe at a lower level than the point of attachment of the pipe K with the cylinder so that any condensed water will drain back into the steam pipe. As shown, the lower end of the cylinder J¹¹ is provided with one or more vents, as indicated at J¹⁴. The portion of the bottom of the cylinder which immediately surrounds the cylindrical passage J¹³ should be finished as indicated at J¹⁵ and L is a piston working in the cylinder J¹¹ having a piston rod extension L¹ which extends through and forms a working fit with the cylindrical passage J¹³. The lower end of this piston rod is formed of reduced diameter as indicated at L² and extends through the port J⁴ so as to contact with the valve J⁵. L³ is an annular shoulder formed at the junction of the piston rod L¹ and its reduced extension L², and L⁴ is a port or passage opening at its lower end through the shoulder L³ and at its upper end opening into an annular passage formed in the piston rod L¹ and indicated at L⁵. This annular passage is located so that when the valve J⁵ is closed and the piston L in corresponding elevated position it will register with vent passages formed through the neck J¹² and indicated at J¹⁶.

At the underside of the piston L and immediately surrounding the piston rod L¹ is formed what may be called a valve indicated at L⁶ which, when the piston is in its lowermost position is seated on the seat indicated at J¹⁵. With the exception of the valve located between the conduit sections G and G¹ and the mechanism and connections for actuating this valve, the structure illustrated and described is old and in normal conditions of operation the valve H is opened so that pressure fluid such as steam or air is admitted to the conduit G connected, as indicated at G², with the outer end of the cylinder F⁶ of the cylinder cocks and the pressure fluid acting on the pistons F⁵ shift and hold these pistons to a position in which they will effect the closing of the valve F³ and as long as the pressure fluid continues to act upon the pistons the valve will remain closed except when the pressure in the cylinder cock chamber F¹ becomes great enough to exert a pressure on the inner ends of the pistons to shift them to positions to open the valve and permit the escape of such water as may have accumulated in the cylinder

cock chambers. When it is desired that the valves F³ should be opened at other times in order to vent the cylinder cocks, the cab valve H is shifted to cut off supply of pressure fluid to the cylinder cocks and vent the pressure fluid in the conduit G and its connections with the cylinder cocks. It is, however, highly desirable that whenever steam supply is cut off from the driving cylinders of the locomotive as by closing of the throttle valve E, that the outlet valves of the cylinder cocks should open so as to exhaust any water which may have accumulated in the cylinder cocks and that as soon as the throttle valve is again actuated to admit steam to the steam pipe leading to the cylinders the outlet valves of the cylinder cocks should promptly close and that this operation should take place without requiring any manipulation of the control valve H and it is to automatically provide for such operations of the cylinder cock valves that our invention is intended and by the construction which we have described the pressure fluid, when the valve H is opened, passes into the valve chamber J³ and if the throttle is closed and no steam admitted into the top of the cylinder J¹¹, the valve J⁵, if not previously seated by the action of the spring J⁶, will be seated and held to its seat by the pressure of the pressure fluid admitted to the valve chamber so that no pressure will be communicated through the conduit section G¹ and its connections with the cylinder cock cylinders F⁶, under which conditions the springs F⁷ will shift the pistons F⁵ and the valves F³ to valve open positions. When the throttle valve is open admitting steam to the steam pipes leading to the driving cylinders, steam will pass from the steam pipe through the pipe K to the top of the cylinder J¹¹ and, acting on the piston L, will move it downward with the result that the piston rod extension L² will move the valve J⁵ away from its seat and permit the passage of pressure fluid into the pipe G¹ and through its connections with the cylinder cock cylinders F⁶ so that the pistons F⁵ are at once shifted to valve closing position. Whenever the throttle is closed, steam pressure is relieved from the top of the piston L so that the valve J⁵ will be seated and, in seating, will, through the contacting piston rod extension L², shift the piston L to its uppermost position and, at the same time, the annular recess L⁵ in the piston rod is brought into registry with the vent passages J¹⁶ so that any pressure fluid contained in the pipe G¹ and its connections is vented with the result that the cylinder cock pistons promptly move to position to open their controlled valves.

If it is desired to vent the cylinder cocks when the throttle valve is opened the engineer, by shifting the valve H, can shut off the supply of pressure fluid to the pipe G and at the same time vent such pressure fluid as may be contained in the pipe G and its connections, with the result that pressure is cut off and the piston F⁵ will, under the pressure exerted by the spring F⁷ and such pressure as may exist in the cylinder cocks, promptly move to valve opening position and at the same time pressure being released in the valve chamber J³ the valve J⁹, which will be held seated as long as pressure exists in the chamber J³, will open by the pressure exerted by the spring J¹⁰ so that any water contained in the valve chamber will be vented.

It will be understood that while the construction of the control valve located between the conduit sections G and G¹ and the mechanism for

actuating this valve is, we believe, especially well adapted for practical use, our invention is not to be understood as limited on any of the details of construction illustrated and described as these details may obviously be changed and modified in many ways.

Having now described our invention, what we claim as new and desire to secure by Letters Patent, is:

- 10 1. In a locomotive engine comprising a boiler, driving cylinders, a steam pipe controlled by a throttle valve connecting the steam space of the boiler with the driving cylinders, cylinder cocks of the type in which means are provided for shifting an exhaust valve to closed position, which means is actuated by fluid under pressure conveyed to the cylinder cocks from a source of pressure fluid by a conduit provided with a valve controllable in the cab of the locomotive and operative to cut off or open connection between the source of fluid pressure and the cylinder cocks, the improvement which consists in providing in
- 15
- 20

the conduit connecting the source of fluid pressure with the cylinder cocks at a point intermediate the valve controllable from the cab of the locomotive and said cylinder cocks, a second valve adapted to open and close said conduit and combining therewith means tending to close said valve when the throttle valve is closed and valve operating means connected with the steam pipe leading from the throttle valve of the locomotive and operative when the throttle valve is open to 10 open the valve and permit passage of the pressure fluid to the cylinder cocks.

2. Mechanism as called for in claim 1, having means operative with the second valve in the pressure fluid conduit leading to the cylinder 15 cocks when said valve is in closed position to permit the exhaust of pressure fluid in the portion of the conduit between said valve and the cylinder cocks.
